UNITED STATES PATENT OFFICE.

GEORGE B. SLOAN, JR., OF OSWEGO, NEW YORK.

FASTENER FOR THE MEETING-RAILS OF SASHES.

SPECIFICATION forming part of Letters Patent No. 471,363, dated March 22, 1892.

Application filed December 31, 1891. Serial No. 416,637. (No model.)

To all whom it may concern:

Be it known that I, GEORGE B. SLOAN, Jr., of Oswego, in the county of Oswego, in the State of New York, have invented new and useful 5 Improvements in Fasteners for the Meeting-Rails of Sashes, of which the following, taken in connection with the accompanying drawings, is a full, clear, and exact description.

This invention is a specific improvement of 10 the sash-lock shown and described in the United States Letters Patent No. 454,628, granted to me June 23, 1891. In the use of said sash-lock I have found that in case the latch was accidentally pushed back to its unlocked 15 position and in engagement with the detent after the sash had been raised sufficient to carry the latch above the releasing-cam the latch thus held by the detent strikes the upper end of the cam and becomes either 20 jammed or broken in the operation of closing the window.

The object of my present invention is to obviate such accidents and to otherwise render the sash-lock more convenient and efficient in 25 its operation; and to that end it consists in the improved construction and combination of parts hereinafter described, and specifically set forth in the claims.

In the annexed drawings, Figure 1 is a top 30 plan view of my improved sash-lock. Figs. 2 and 3 are inverted plan views of the latch-case and showing, respectively, the latch in full lines and in dotted lines. Fig. 4 is a side view of the sash-lock. Fig. 5 is an inner face view of 35 the catch-plate, and Fig. 6 is a vertical transverse section on line xx in Fig. 2.

Similar letters of reference indicate corresponding parts.

C represents the catch-plate, which is attached to the top of the meeting-rail R of the upper sash. This catch-plate I provide with the rigid upward-projecting hook a, as shown in my patent hereinbefore referred to. b denotes the rigid cam, which also projects vertically from the plate C; but in this case the said cam is formed with the beveled overhanging face b' on its inner side and extending to the side facing the hook a, as shown in Fig. 5 of the drawings.

A represents the case, which is attached to the top of the meeting-rail R' of the lower

sash. The top plate of said case is provided with a slot e, which is elongated in the direction of the length of the latch l, which is rigidly secured to the stud o, passing through the slot and integral with the handle h, which is mounted on the top of the case and constitutes a part of the latch. The spring s forces the latch longitudinally outward and also toward its locking position. The outer end of the latch l is provided with a laterally-projecting shoulder l' for the purpose hereinafter explained. A suitable detent f on the case A serves to partly hold the latch in its unlocked position. This detent I preferably form on the exterior of the vertical wall of the case and form the handle portion h of the latch with a downward extension h', which engages the detent, which is of the form of a shoulder, as shown.

In the operation of the described sash-lock 70 the engagement of the latch l with the hook a locks the window. To open the window, the latch has to be swung away from under the hook and around sufficiently to cause the handle portion h of the latch to engage the detent 75 f, by which it is retained, and thus the latch is confined in its unlocked position, so as to enable the operator to use both hands in raising the sash. In this latter movement the shoulder l' of the latch is opposed to the overhanging face b' of the cam b, which forces the latch longitudinally back toward the case A and allows the shoulder l' to slide over the cam, and in passing over the upper end of the cam-face the latch is forced back sufficiently 80 to cause the handle portion h of the latch to become released from the detent f. The latch then springs automatically toward its locking position. The cam-face is higher than the shoulder of the hook a, so as to prevent the 85 latch from catching under the hook a while raising the sash. In closing the sash the latch yields to the contact with the beveled top of the hook and then springs into engagement with the shoulder of the hook. In case the latch is accidentally turned back to its unlocked position after it has passed above the cam and then the sash pushed down, the latch will yield longitudinally to the pressure of the top of the cam and cause the handle h to be 90 released from the detent, when the latch will 95 spring into its locked position.

Having described my invention, what I claim as new, and desire to secure by Letters Patent, is—

1. In combination with the locking-hook, a swinging and longitudinally-movable latch, a detent retaining the latch in its unlocked position, a cam moving the latch longitudinally and releasing the same from the detent, and a spring forcing the latch into its locking position, as set forth.
2. In combination with the hook *a*, the rigid cam *b*, formed with the beveled overhanging face *b'* on its inner side, the case *A*, provided with the slot *e* and detent *f* on its exterior, the

latch *l*, pivoted in said slot and provided with the shoulder *l'* for engaging the cam, the handle *h*, mounted on the case and fixed to the latch and formed with the downward extension *h'*, adapted to engage the detent, and a spring in the case, forcing the latch toward its locking position, substantially as described and shown.

In testimony whereof I have hereunto signed my name this 28th day of December, 1891.

GEORGE B. SLOAN, JR. [L. S.]
